UNITED STATES PATENT OFFICE.

MAX MICHAEL, OF CHEMNITZ, GERMANY, ASSIGNOR TO THE FIRM OF SCHUBERT & SALZER MASCHINENFABRIK, AKTIENGESELLSCHAFT, OF CHEMNITZ, GERMANY.

STRAIGHT HOSEIERY-FRAME.

1,138,391.

Specification of Letters Patent. Patented May 4, 1915.

Application filed March 27, 1914. Serial No. 827,719.

To all whom it may concern:

Be it known that I, MAX MICHAEL, a citizen of the German Empire, residing at Chemnitz, in the Kingdom of Saxony, Germany, have invented certain new and useful Improvements in Straight Hosiery-Frames; and I do hereby declare the following to be a full, clear, and exact description of the invention, such as will enable others skilled 10 in the art to which it appertains to make and use the same.

My invention relates to improvements in straight hosiery frames, and more particularly in hosiery frames, in which stop or retarding members are provided for retarding the speed of the thread guides. A frame of this class is described in the patent of the United States to Lieberknecht Nr. 981,663, of January 17, 1911. As described in the 15 said patent the object of the retarding or stop member's is to soften the shocks or blows which are produced when the thread guide bars strike on their stops. As shown in the said patent the speed of the thread guides is retarded by gradually reducing the speed 20 almost to zero, as the thread guide bar approaches the end of its stroke. In the co-pending application Ser. No. 805328, a hosiery frame is shown in which the speed 25 of the thread guide bars is reduced to about one half the ordinary speed of the knitting operation, which reduction has been found sufficient for practical purposes and permits the use of comparatively simple retarding 30 means.

The object of my present improvements is to provide stop or retarding mechanism which can more easily be mounted on the frame than levers and the like, which can 40 frequently not be provided in the frames because they require too much space, so that the size of the machine must be increased in order to prevent the levers from interfering with other parts of the machine.

With this object in view my invention 45 consists in providing gear wheels and racks in combination with the stop members, which can be mounted at any desired place of the machine between the rod for retarding the thread guide and the slur connecting bar, and which do not interfere with other 50 mechanisms and require little space.

For the purpose of explaining the invention an example embodying the same has 55 been shown in the accompanying drawing,

in which the same letters of reference have been used in all the views to indicate corresponding parts.

In said drawing—Figure 1, is a front view of the mechanism and the parts coöperating therewith, Fig. 2, is an enlarged detail view, Fig. 3, is a side view of Fig. 2 seen from the left, and Fig. 4, is a similar side view of Fig. 2 seen from the right.

In the example illustrated in the drawings 65 the hosiery frame is provided with a slur connecting bar *a* of usual construction, which is adapted to be reciprocated from a knitting cam *b* through the intermediary of a rod *c*, a rocking knitting lever *d* and a connecting rod *e*. On the bar *a* the member for carrying along the thread guide bar *h* provided with a thread guide *i* is mounted, which member consists of a bar *f* secured to brackets *f'* mounted on the bar *a*. The bar *f* 70 is frictionally engaged by an arm *g* which is adapted to carry along the thread guide bar *h*. The said carrying mechanism depends upon the movement of the knitting mechanism, and the same speed is imparted 75 thereto as to the knitting mechanism, and the said speed is transmitted to the thread guide bar *h*.

The mechanism so far described is known 80 in hosiery frames. In the example illustrated in the drawing, the improved retarding mechanism connected with the knitting mechanism is constructed as follows: The slur connecting bar *a* is provided at one of its ends with rack teeth *t*. On the frame *o* 85 of the machine a bracket *p* is mounted which provides a support for short shafts *u* and *v* on which gear wheels *w* and *x*, *y* are mounted. The gear wheel *w* which is mounted on the axis *u* is in mesh with the rack teeth of 90 the bar *a*. The gear wheels *x* and *y* which are mounted on the axis *v* are rigidly connected with each other, and they have different diameters. The gear wheel *x*—the 95 diameter of which is greater than that of the gear wheel *y* is in mesh with the gear wheel *w*, while the small gear wheel *y* is in mesh with rack teeth *z* of a rod *l* which is mounted for reciprocation in suitable bearings *m*. The movement of the slur connecting bar *a* is transmitted through the rack *t*, the gear wheels *w*, *x*, and *y*, and the rack *z* to a rod *l* which forms a part of the retarding mechanism of the thread guide. The 100 number of the teeth of the gear wheel *x* is 105 110

the double of that of the teeth of the gear wheel w , so that the velocity of the thread guide retarding rod l is only one half of that of the bar a . Therefore the retarding members or stops s^1 and s^2 are overtaken by the arm g of the thread guide bar prior to the end of the stroke of the thread guide. Thereupon the thread guide bar h is retarded, because it must assume the speed of the rod l which is less than that of the rod h , until the thread guides arrive at the end of their stroke which is determined by the stop h . This is possible, because the thread guide carrying arm g is adapted to slide on the rod f the speed of which is not retarded.

The same operation is repeated in both knitting directions, the stop members s^1 and s^2 being alternately thrown into operation.

I claim herein as my invention:

- 20 1. In a hosiery frame, the combination with a reciprocable connecting bar, and a thread guide bar frictionally connected with the latter, of a stop member adapted to retard the movement of the thread guide bar, and gearing interposed between the stop member and the connecting bar adapted to impart to said stop member a continuous and uniform movement in the direction of the movement of the movement of said bars.
- 25 2. In a hosiery frame, the combination with a reciprocable connecting bar, and a thread guide bar frictionally connected

with the latter, of a stop member adapted to retard the movement of the thread guide bar, and rack and pinion mechanism interposed between the stop member and the connecting bar adapted to impart to said stop member a continuous and uniform movement in the direction of the movement of the said bars.

3. In a hosiery frame, the combination with a reciprocating slur connecting bar, and a thread guide bar frictionally connected with said slur connecting bar, of a rod carrying at least one stop member disposed in position for being overtaken by said thread guide bar and adapted to retard the same, rack teeth provided at adjacent ends of the slur connecting bar and the said rod, and gear wheels interposed between said stop member and the slur connecting bar, engaging said rack teeth and adapted to impart to the said stop member reciprocating movement of reduced speed and in the direction of the movement of the slur connecting bar and thread guide bar.

In testimony whereof I hereunto affix my signature in the presence of two witnesses on this 2nd day of March, 1914.

MAX MICHAEL.
